UNITED STATES PATENT OFFICE.

ROYAL VINCENT CRAIG, OF ANNADALE, PRINCE BAY, NEW YORK.

PROTECTIVE DEVICE.

Application filed June 12, 1925. Serial No. 36,727.

To all whom it may concern:

Be it known that I, ROYAL VINCENT CRAIG, a citizen of United States, residing at Annadale, Prince Bay, Staten Island, in the county of Richmond and State of New York, have invented new and useful Improvements in Protective Devices, of which the following is a specification.

This invention relates to improvements in protective devices for use against "hold-ups."

The principal object of the invention resides in a means for shielding the clerk of a store, bank or other like place of business, against gun fire by a bandit or robber in the event of an attempted robbery and which means is operated by the victim in a manner as to not cause suspicion on the part of the bandit.

Another object of the invention is to provide a bullet proof shield which is normally held in a concealed position beneath the counter of a store by the use of a sensitive member which is adapted to be released by the depression of a treadle bar which in turn causes a spring means to automatically move said shield with great rapidity to a position above the counter, thus forming a partition between the opposite sides of the counter, and which shield is adapted to close an electric circuit upon reaching the limit of its closing movement to visually or audibly sound an alarm to persons outside the building in which the device is installed thereby indicating that an attempted hold-up is occurring within.

With these and other objects in view, the invention resides in certain novel construction and combination and arrangement of parts, the essential features of which are hereinafter fully described, are particularly pointed out in the appended claim, and are illustrated in the accompanying drawing, in which:

Figure 1 is a perspective view of my invention installed with the shield in a lowered or set position.

Figure 2 is a vertical transverse sectional view on the line 2-2 of Figure 1, with the shield in a raised position as indicated in dotted lines.

Figure 3 is a horizontal sectional view on the line 3-3 of Figure 1.

Referring more particularly to the drawing, the reference numeral 10 designates a counter, and 11 the frame work surrounding

the same which defines a window opening 12, and behind which the clerk of a store or bank is adapted to be positioned in the performance of his duties. It is behind such a counter that my invention is adapted to be installed and which is shown in its entirety as at 13.

The apparatus 13 comprises a shield or panel 14 of bullet proof material such as hard steel in order to withstand the effects of gun fire. The top of the shield is provided with eyes 15 which overhang the side edges of the shield and are formed with elongated openings for the passage of vertical rods 16 which extend from the floor to the top of the window and are disposed adjacent to side walls of the window. Guide rails 17 are secured to the side walls of the window for guiding the shield in its sliding movement. Expansion springs 18 surround the rods 16 and are interposed between the eyes 15 and the floor, and which normally tend to move the shield to a position to close the window opening 12.

For normally concealing the shield beneath the window and counter and against the action of the springs 18, there is provided a trigger member 19 which is pivotally mounted on the floor midway between the rods 16. The trigger member is formed with a bill 20 for movement into an opening 21 in the shield adjacent the lower edge thereof, while a tail 22 formed on the trigger extends upward at an angle with respect to the floor. A treadle bar 23 is slidably mounted in the path of the tail 22 and is normally disposed out of engagement with the tail by the action of flat springs 24 carried by the underside of the treadle bar and which engage the floor. The treadle bar is limited in its upward movement by stops 25 carried at the top of a pair of rails or post 26 on which the treadle bar is slidable.

In operation, we shall presume that the shield is in a set position beneath the counter and the trigger in engagement with the shield for holding the same down against the action of the springs 18. A robber now enters the store and demands the clerk behind the counter to "throw-up his hands" at which time the clerk promptly obeys but simultaneously presses his foot upon the treadle bar 23, depressing the same and causing the bar to engage the tail of the trigger which causes the bill of the trigger to free the shield, at which time the springs

18 move the shield to a raised position with great rapidity. This provides a barrier between opposite sides of the counter which protects the life of the clerk against gun fire. When the pressure of the foot is released on the treadle bar, the same is moved to a normal position by the action of the springs 24. It will be noted that by extending the treadle bar the entire length of 10 the counter as shown in the drawing, the same may be actuated by the clerk standing in position along the counter.

In order to give warning to those outside the building that an attempted robbery 15 is occurring within, I provide a signal which includes a pair of contacts 27 and 28 arranged at the top of the window frame, the same being normally spaced and arranged in an electric circuit 29. The circuit includes a signal in the nature of a lamp or bell 30 and a source of energy such as a battery 31. As the shield reaches the limit 20 of its upward movement, the contacts 27 and 28 will be brought into co-acting position, thus closing the circuit at which time 25 the bell will sound or the lamp be lighted.

If desired, peep openings 32 may be provided in the shield for the accommodation of the person behind the counter in order that he may view the further actions of the bandit or robber. Of course, these openings will be of such size as to prevent a gun being inserted therethrough.

What is claimed as new is:—

In a device of the class described, the 35 combination with a window, a shield slidably mounted in the side walls thereof, springs for normally holding said shield in a raised position to cover the window opening, a pivotally mounted trigger; co-acting 40 means between said trigger and said shield for holding said shield in a concealed position behind said window, a tail extending from said trigger, a vertically movable treadle bar in the path of said tail for releasing said co-acting means, and springs for 45 normally holding said treadle bar out of engagement with said tail.

In testimony whereof I have affixed my signature.

ROYAL CRAIG.
